CARPET OR THE LIKE

Charles D. Lehner, Long Island City, N. Y., assignor to Bigelow-Sanford Carpet Co., Inc., Thompsonville, Conn., a corporation of Massachusetts

Application October 6, 1948, Serial No. 148,984

Term of patent 14 years

(Cl. D92—4)

To all whom it may concern:

Be it known that I, Charles D. Lehner, a citizen of the United States, residing at Long Island City, in the county of Queens and State of New York, have invented a new, original, and ornamental Design for a Carpet or the like, of which the following is a specification, reference being had to the accompanying drawing, forming a part thereof.

The figure of the drawing is a plan view of a carpet embodying my new design, a repeat unit of which is defined by the broken horizontal and vertical lines. The design unit is repeated as indicated.

I claim:

The ornamental design for a carpet or the like, as shown and described.

CHARLES D. LEHNER.
